(57) **CLAIM**

The ornamental design for a “lid handle for an article of cookware,” as shown and described.

DESCRIPTION

FIG. 1 is an enlarged perspective view of a “lid handle for an article of cookware” showing my new design;

FIG. 2 is a top plan view thereof;

FIG. 3 is a front side elevational view thereof;

FIG. 4 is a left side elevational view thereof;

FIG. 5 is a right side elevational view thereof;

FIG. 6 is a rear elevational view thereof; and,

FIG. 7 is a bottom plan view thereof.

The “lid for article of cookware” shown in phantom lines depicts the environment of my new design and forms no part of the claimed design.
